CLAIM

The ornamental design of a wearable apparatus for personal intuition based cognitive assistant, as shown and described.

DESCRIPTION

FIG. 1 is a front elevational view of a second embodiment of a wearable apparatus for personal intuition based cognitive assistant according to our new design;

FIG. 2 is a back elevational view of a second embodiment of a wearable apparatus for personal intuition based cognitive assistant according to our new design;

FIG. 3 is a right elevational view of a second embodiment of a wearable apparatus for personal intuition based cognitive assistant according to our new design;

FIG. 4 is a right view of a second embodiment of a wearable apparatus for personal intuition based cognitive assistant according to our new design;

FIG. 5 is a top plan view of a second embodiment in a closed state of a wearable apparatus for personal intuition based cognitive assistant according to our new design; and,

FIG. 6 is a top plan view of a second embodiment in an expandable open state of a wearable apparatus for personal intuition based cognitive assistant according to our new design.

The broken lines depict environment only and form no part of the claimed design.
